UNITED STATES PATENT OFFICE

112,530

DESIGN FOR A COMBINED BACK GUARD PANEL AND SUPPORT FOR TIMER, LAMP, AND CONDIMENTS SET FOR STOVES

Ralph E. Kruck, Springfield, Mass., assignor to Florence Stove Company, Gardner, Mass., a corporation of Massachusetts

Application February 7, 1938, Serial No. 74,926

Term of patent 3½ years

To all whom it may concern:

Be it known that I, Ralph E. Kruck, a citizen of the United States, residing at Springfield, in the county of Hampden, State of Massachusetts, have invented a new, original, and ornamental Design for a Combined Back Guard Panel and Support for a Timer, Lamp, and Condiment Set, for Stoves, of which the following is a specification, reference being had to the accompanying drawing, forming part thereof.

Fig. 1 is a top plan view of a combined back guard panel and support for timer, lamp, and condiment set, for stoves, showing my new design.

Fig. 2 is a front perspective.

Fig. 3 is an end elevational view thereof.

I claim:

The ornamental design for a combined back guard panel and support for timer, lamp, and condiment set, for stoves, as shown and described.

RALPH E. KRUCK.
